UNITED STATES PATENT OFFICE

2,414,377

MACHINE FOR CHAMFERING DIES

Franklin Judge, Greenfield, Mass.

Application April 29, 1944, Serial No. 533,283

1 Claim. (Cl. 51—46)

1

This invention relates to a grinding machine particularly designed for chamfering the lead ends of the spaced toothed lands of a hollow annular and internally threaded die, such as an acorn die.

It is the general object of my invention to provide improved means by which the lead ends of the lands may be accurately chamfered and thereby sharpened and may also be suitably relieved. I also provide for a quick return of the wheel and work to their initial relation after the grinding for each land is completed.

A further feature of the invention relates to the provision of improved means for moving the grinding wheel toward and from the work in any angular position of the grinding wheel axis.

My invention further relates to arrangements and combinations of parts which will be herein-after described and more particularly pointed out in the appended claim.

A preferred form of the invention is shown in the drawings, in which

Fig. 1 is a plan view of my improved chamfering machine;

Fig. 2 is an end elevation of the die-holding head, looking in the direction of the arrow 2 in Fig. 1;

Fig. 3 is a front elevation of the die-holding head, partly in section and looking in the direction of the arrow 3 in Fig. 2;

Fig. 4 is an end elevation of the grinding wheel head, looking in the direction of the arrow 4 in Fig. 1; and

Fig. 5 is a front elevation of the grinding wheel head, looking in the direction of the arrow 5 in Fig. 4.

Referring to the drawings, my improved die chamfering machine comprises a work supporting head H and a grinding wheel head G, both mounted on a supporting base or table 10. The grinding wheel head G is pivotally connected by a stud 11 to the base 10, so that it may be angularly adjusted on the base to vary the chamfer angle. Clamps 12 are provided to hold the grinding wheel head in adjusted angular position.

The work K, shown herein as an acorn die, is mounted at the end of a work spindle 14 (Fig. 3) and is firmly secured thereto by a clamping sleeve 15 and lock nut 16 which are threaded on a driving bushing 17. The bushing 17 is secured to the tapered end of the spindle 14 by an internally flanged clamping bushing 18.

The details of construction of the work holder are not claimed herein, as they form the subject matter of a copending application, Serial No.

2

520,917, filed February 3, 1944, which issued as Patent 2,385,922, Oct. 2, 1945.

The work spindle 14 is rotatably mounted in ball bearings 20 in a work support 21 pivoted on a cross shaft 22 having a bearing 23 on a work slide 24. The slide 24 is mounted in dove-tailed guideways 25 (Fig. 2) on a cross slide 26 and may be manually adjusted thereon axially of the work spindle by a handle 27 which is operative through the usual feed screw and nut.

The cross slide 26 (Fig. 3) is similarly mounted in dove-tailed guideways 27a on the base 10 and may be adjusted forward and rearward on said base by a hand wheel 28 which is operative through another feed screw and nut.

Swinging movement for relieving purposes is imparted to the work support 21 by rotation of a cam shaft 30, mounted in bearings 31 in a rearward extension 32 of the work support 21. A handle 33 (Fig. 1) is provided for manually rotating the cam shaft 30.

Change gears 35 connect the shaft 30 to the work spindle 14, and the gears 35 are so selected that one revolution of the cam shaft 30 will correspond to an angular advance of the work spindle 14 equal to the angular relation of successive lands of the die or work K. For a die having four lands, the ratio of movement between the shafts 30 and 14 would be four to one, and the shaft 14 would advance 90° for each revolution of the cam shaft 30.

A scroll cam 37 (Fig. 2) is mounted on the cam shaft 30 and engages a roll 38 rotatably mounted on a stand 39 fixed on the wheel slide 24. As the cam shaft 30 is manually rotated, the cam 37 reacts against the roll 38 and swings the work K toward the grinding wheel W to relieve the chamfered end of the land being sharpened.

As one grinding operation is completed, the shoulder 37a of the cam 37 clears the roll 38 and permits an abrupt return movement of the work holder to its initial position for starting the next grinding operation. Contact of the cam and roll is maintained by the rearward overhang of the work head portion 32. The relieving movement is very slight and the drop of the cam is much exaggerated for clearness.

A work setting arm 40 (Fig. 3) is mounted at the end of a supporting rod 41 slidably in bearings 42 on the top of the work head 21. Screws 43 hold the rod 41 in adjusted position. When a die is to be mounted on the work spindle, the cam shaft 30 is rotated to bring the cam 37 to starting position. One of the lands of the die or work K is then engaged with the arm 40 before

the flanged bushing 18 is tightened to secure the work holder on the work spindle 14.

The grinding wheel W is mounted on a wheel spindle 50 rotatable in bearings in a wheel support 51 which is slideable axially in a wheel head 52 and which may be secured in axially adjusted position by clamping screws 53. The wheel head 52 is mounted for vertical adjustment in dovetailed guideways 55 formed on the face of a wheel head support 56. Such vertical adjustment is accomplished by a handle 57, feed screw 58 and nut 59 (Fig. 4).

The support 56 is integral with a wheel head carriage 60 (Fig. 4) mounted on longitudinally extending roller or ball bearings 61. The wheel head carriage may thus be moved axially of the grinding wheel spindle and toward and away from the work.

Such movement of the wheel head carriage 60 is preferably accomplished manually through a hand lever 63 mounted on a pivot post 64 (Fig. 4) secured to a bearing plate 65 which is pivoted at 11 to the base 10 as previously described. The plate 65 supports the ball bearings 61. The lever 63 is connected by a link 66 to a portion of the wheel head carriage 60 and thus provides convenient means for manually reciprocating the grinding wheel axially relative to the work K.

The grinding wheel W may be driven by an electric or air motor contained in the sleeve 51 or may be provided, as shown in the drawings, with a pulley 70 connected by a belt 71 to a larger pulley 72 on the armature shaft of a motor M. The motor is mounted in a support 75 pivoted at 76 to the carriage 60 and is adapted to swing forward or rearward to maintain uniform belt tension as the wheel head 52 is adjusted vertically on the support 56. A spring 77 tends to

swing the motor M with its support 75 rearward to take up any slack in the belt 71.

My improved grinding machine is thus particularly well adapted for grinding internal or acorn dies, and embodies provision for accurately mounting such a die, for selectively positioning the die both axially and transversely relative to the grinding wheel, for oscillating the work head and die to relieve the chamfered cutting edges, for adjusting the grinding wheel angularly and vertically relative to the work, and for manually reciprocating the grinding wheel toward and away from the work.

I have also provided improved means for quickly returning the work to its initial sharpening position relative to the grinding wheel after sharpening and relieving each land, and for angularly advancing the work in predetermined relation to the rotation of the relieving cam.

Having thus described my invention and the advantages thereof, I do not wish to be limited to the details herein disclosed, otherwise than as set forth in the claim, but what I claim is:

In a die chamfering machine, a base, a work head mounted to swing on said base about an axis parallel to the work head axis, a work spindle rotatable in said head, means to clamp a die to the end of said work spindle, a positioning arm mounted on said swinging work head and effective to engage a land of the die and to thereby angularly position the work in the work head in every position of said head, a supporting rod on which said arm is freely pivoted and movable into and out of operative position, clamping bearings on said work head in which said rod is axially and angularly movable, and means to secure said rod in a selected position in said bearings.

FRANKLIN JUDGE.
